CLOCK RADIO

John K. Miles and Odin D. Lingle, Columbus, Ind.,
assignors to Arvin Industries, Inc., Columbus, Ind., a
corporation of Indiana

Filed Dec. 26, 1967, Ser. No. 9,914

Term of patent 14 years

Int. Cl. D14—03; D10—03, 99

U.S. Cl. D56—4

Fig. 1

Fig. 2

Fig. 3

Fig. 4

Fig. 5

FIG. 1 is a front elevational view of a clock radio showing our new design;

FIG. 2 is a left side elevational view, the right side being substantially a mirror image thereof;

FIG. 3 is a rear elevational view;

FIG. 4 is a plan view; and

FIG. 5 is a side, top and front perspective view thereof.

The dominant features of the design are shown in full lines.

We claim:

The ornamental design for a clock radio, as shown and described.
